UNITED STATES PATENT OFFICE

HARRY P. CATO, OF VALLEY, NEBRASKA

COMPUTING MACHINE

Application filed May 1, 1930. Serial No. 449,044.

This invention provides a device intended chiefly for use at stations dispensing motor fuel, lubricating oil and other liquid to indicate the cost of a definite amount of the 5 article.

A device of the character aforesaid is particularly advantageous when the price is fractional as it obviates calculation and indicates a cost equitable to both the purchaser and 10 dispenser when the computation is not even, that is, includes a fraction.

The machine comprises an elongated casing having an observation opening in its front and a quantity indicating scale adjacent 15 the observation opening, rollers within the casing upon opposite sides of the observation opening, gearing connecting the rollers at one end to impart a reverse rotation thereto, and a computing web, sheet or strip 20 attached at its ends to the rollers and adapted to be wound upon one and simultaneously unwound from the other, said web being provided with columns of figures indicating computations, or total costs, and said computation columns having price headings. 25

While the drawings illustrate a preferred embodiment of the invention, it is to be understood that in adapting the means to meet specific needs and requirements, the design 30 may be varied and changes in the minor details of construction may be resorted to within the scope of the invention as claimed without departing from the spirit thereof.

For a full understanding of the invention 35 and the merits thereof, reference is to be had to the following description and the drawings hereto attached, in which:

Figure 1 is an elevational view of a computing machine illustrative of an embodiment 40 of the invention.

Figure 2 is a vertical transverse sectional view on the line 2—2 of Figure 1.

Figure 3 is an elevational view of the interior mechanism removed from the casing, 45 parts being broken away and the computing strip omitted.

Figure 4 is an enlarged sectional view on the line 4—4 of Figure 1, looking in the direction of the arrows.

Figure 5 is a detail sectional view on the

line 5—5 of Figure 3, the parts being shown on a larger scale.

Corresponding and like parts are referred to in the following description and indicated in the several views of the drawings by like 55 reference characters.

The machine is elongated and comprises a casing closed at its ends by caps and an interior mechanism readily removable from the casing and including a framework, a web, 60 rollers therefor, and gearing for simultaneously operating the rollers to wind the web upon one and unwind it from the other.

The casing is preferably of sheet metal and comprises a back 1, sides 2, and a front 3, in 65 which is formed an observation opening 4 to expose the readings on the web 5. The sides 2 extend a slight distance beyond the front 3 and terminate in flanges 6 which are disposed inwardly to overlap side portions of a glass front 7. The front 3 has side portions bent to form flanges 8 which are disposed against the inner faces of the sides 2 to which they are soldered or otherwise rigidly attached. This results in the formation 70

of a stiff and rigid structure adjacent the front of the casing. A card 9 is located between the front 3 and glass 7 and has an opening coinciding with the observation opening 4 to expose the columns of figures on the 80 computing web 5. The card 9 is provided with an index at one side of the observation opening to designate quantity. The indicating scale 10 bears numbers from 1 to 20, representing gallons of motor fuel or other liquid 85

to be dispensed. The opposite side portion of the card 9 may bear any legend for the information of the customer such as "Tax included". Similar caps 11 and 12 close the ends of the casing and operate to retain 90 the interior mechanism in position. Any suitable means may be employed to secure the caps when slipped upon the ends of the casing. Screws 13 are employed and pass through the rims of the caps and sides of 95 the casing and enter blocks 14 and 15 disposed within end portions of the casing.

The upper block 14 is solid whereas the lower block has a recess 16 formed in its upper side which is closed by a plate 17 100

secured to the block 15 by suitable fastening means. Rollers 18 are mounted in the blocks 14 and 15 and the ends of the web 5 are attached thereto to admit of winding the 5 web upon either one of the rollers when the same is rotated. Spur gears 19 fast to the lower ends of the rollers 18 are in mesh with an idle gear 20 so that rotation of the gear 20 will effect reverse rotation of the rollers 10 18 to positively wind the web 5 upon one of the rollers and unwind it from the other roller. The gear wheels 19 and 20 are located in the recess 16 and, for convenience, the idle gear 20 is adapted to be rotated by means of 15 a key 21, which is engaged with the gear 20 when it is desired to adjust the web 5 to bring a particular column of computation figures in position to be read through the observation opening 4. A plate 22 is connected at its ends to the blocks 14 and 15 and forms a support for that portion of the web 5 opposite the observation opening 4.

The web 5 may consist of a strip or sheet of stout paper or stiffened fabric and may be 20 of any length, and is provided upon one side with columns of figures representing computations, said columns having price headings which, in conjunction with the quantity scale, indicates the price within the limit of 25 the quantity scale. That portion of the web 5 opposite the observation opening 4 is held close to the glass 7 by the plate 22 so that the figures representing the computations may be easily read. It is understood that the 30 vice is conspicuously positioned for convenience of the customer as well as the dispenser. When the price changes the web 5 is adjusted to bring the price heading opposite the observation opening 4. As shown in 35 Figure 1 of the drawings, the price heading is 21 $\frac{3}{4}$. The cost of one gallon is indicated on the computing scale as 22, it being understood that allowance must be made for the fraction. Four gallons of motor fuel at 21 $\frac{3}{4}$ 40 cents per gallon is 87 even, as indicated on the computing scale. The total cost of any number of gallons from one to twenty inclusive, is indicated on the figure of the computing scale opposite the amount of the quantity 45 scale, as will be readily comprehended.

What is claimed is:

A computing device comprising a casing 50 open at its ends and front, a front plate having a central elongated observation opening 55 and having its side edges bent to form forwardly projecting flanges bearing against and permanently secured to the sides of the casing, said sides of the casing being bent to form inwardly extending flanges bearing 60 against and extending laterally beyond the ends of the flanges on the front plate to form an intermediate pocket, a card seated in said pocket and having an opening registering with the observation opening, a transparent 65 cover fitted in the pocket and extending over

the card and the opening in the card and front plate and bearing against the flanges on the sides of the casing whereby said flanges will hold the cover and card within the pocket and against the front plate, blocks at the ends 70 of the casing bearing against the inner side of the front plate and having their forward edges cut away to form seating recesses, a connecting plate seated at its ends in the recesses of the blocks immediately back of the 75 observation opening, caps of substantially the same height as the thickness of the blocks fitted over the ends of the casing and secured to said blocks and casing, and a web supported by and movable transversely over 80 said connecting plate at the rear of the front plate, said web and card bearing correlated data.

In testimony whereof I affix my signature.
